VENTILATING SYSTEM

Application filed May 10, 1926. Serial No. 108,004.

This invention relates to improvements in ventilating apparatus and more particularly to apparatus for installation and use in places for public gatherings, such as theaters, school rooms, churches and passenger coaches.

Efforts to secure comfort in crowded theaters, school rooms, churches and other places for public gatherings have led to finally accepted practice of supplying a vast volume of air which is commonly washed and either cooled or warmed and delivering it at scattered points throughout a room or space and then exhausting it to waste. The air quantities thus handled range from thirty (30) 10 to fifty (50) cubic feet per person per minute, although less than a cubic foot per person per minute is actually breathed, the remainder being necessary for dilution and air movement, but, because it becomes contaminated 15 and unfitted for breathing purposes this air is exhausted, as waste, carrying with it the positive or negative heat with which it was tempered. This practice and only by the 20 closest temperature and humidity regulation, affords, at best, only average comfort conditions.

Among the objects of our invention is the provision of means whereby each individual person, as seated in a place for public gathering, may surround himself in an atmosphere conditioned and controlled to meet his personal needs and desires.

Our improvements consist in the novel construction, arrangement and combination of parts as hereinafter fully, clearly and concisely described, definitely pointed out in our claims and illustrated by the accompanying drawing (1 sheet) in which:

Fig. 1 is a diagrammatical floor plan of a place for public gathering and shows an apparatus for conditioning and delivering air in accordance with our invention;

Fig. 2 shows in rear elevation a group of seats equipped with controllable discharge outlets for air;

Fig. 3 shows in side elevation the group of seats as shown in Fig. 2;

Fig. 4 is an enlarged sectional detail of the discharge nozzle;

Figs. 5 and 6 illustrate a modified form of a controllable outlet.

Referring more specifically to the drawing, 10 designates a room or chamber, which is temperature-controlled, as by any approved 55 heating or cooling system, not shown.

For the supply of breathing air to the room, we provide an air conditioner 11, which may be of any approved type and construction, such as a washer with air tempering means. 60 From this conditioner we provide main ducts 12 having branches 13, which latter lead to the vicinities of fixed seats, such as the rows of seats 14, shown diagrammatically in Fig. 1. At the discharge end of each branch duct 65 we provide a nozzle 15, as best shown in Fig. 4, adapted to control both the flow and direction of the breathing air from the conditioner, to the end that the occupant of the seat may provide himself with the breathing and comfort condition of his individual 70 need and desire.

As a means of mounting the nozzle 15, we utilize the seat supporting standard 16, which is of a tubiform structure and communicates with the air conditioner through ducts 12 and 13.

As best shown in Fig. 4, the nozzle is connected with the top of the standard by means of a swivel-joint 17, whereby to provide selective lateral angularity of the discharging current of conditioned air.

To provide selective vertical angularity of the discharge current of air, we provide a bearing 18 within the nozzle and mount there-in a manually rotatable barrel 19, having substantially diametrically opposed intake and outlet ports 20 and 21, respectively, and a projecting manipulating handle wheel 22.

To control the volume of discharging air, we provide a damper such as 23, for closing or grading the opening of the intake port 20.

We contemplate the provision of a nozzle, as recited, for each occupant of each seat, to the end that breathing air may be supplied to each individual member of an audience, according to his needs and desires and this all independent of the general air tempering of the audience chamber.

In the form shown in Figs. 5 and 6, we show 100

a discharge outlet in the form of a register carried at the back of a theater seat and connected with an air condition apparatus in substantially the same manner shown in the preferred form and which connection includes a normally closed valve 30 comprising a pedal 31 and a spring 32.

In this form the operator while seated in the vicinity of the register holds the valve open when he desires the benefit of breathing air independent of the tempered air of the room. In this form of apparatus, the valve being normally closed, there is economy in operation in view of the fact that the supply of breathing air is available only upon a manual holding of the flow valve open.

We claim:—

1. In a device of the class described, a source of air supply, a nozzle in communication therewith, said nozzle having a contracted throat portion, a valve consisting of a sleeve having diametrically opposite ports, said valve being located in said throat portion of said nozzle to control the supply of air therethrough, means for manually operating said valve, said nozzle having an expanded terminal portion beyond said throat portion, a screen to guard said terminal portion located at the most expanded portion thereof, and a swivel support for said nozzle.

2. In combination, a chair having a hollow supporting standard, a source of air communicating with said standard, a nozzle swivelably mounted upon said standard and adapted to control the horizontal direction of air flow, a valve in said nozzle to control the air supply, means in said valve for controlling the vertical direction of air flow.
